DRY SHAVER

Edwin Jacobsen, Altadena, Calif.

Application June 9, 1937, Serial No. 147,333

11 Claims. (Cl. 30—43)

My invention relates to dry shavers that may be operated by hand or power and are particularly adapted to clip the beard and hair.

The primary object of my invention is to provide a dry shaver that will give a close shave rapidly.

A further object of my invention is to provide a dry shaver that may be carried in one's vest pocket.

10 A further object of my invention is to provide a dry shaver wherein the beard is cut by two cutting edges coming together on the same plane.

15 A further object of my invention is to provide a dry shaver wherein the cutting blade may be cheaply and quickly replaced.

A further object of my invention is to produce a power dry shaver that will meet the requirements of the barbers.

20 With these and incidental objects in view, the invention consists in certain novel features of construction and combination of parts, the essential elements of which are set forth in the appended claims, and a preferred form of embodiment of which is hereinafter shown with reference to the drawings which accompany and form a part of this specification.

In the drawings:

Fig. 1 is a side elevation of the hand operated 30 dry shaver.

Fig. 2 is a cross sectional view taken on line 2—2 Fig. 1, looking in the direction indicated.

Fig. 3 is a fragmentary cross sectional view taken on line 3—3, Fig. 2 looking in the direction indicated.

Fig. 4 is a fragmentary bottom elevation of a shear type of blade that may be used with my shaver.

Fig. 5 is a cross sectional view taken on line 40 5—5, Fig. 4, looking in the direction indicated.

Fig. 6 is a longitudinal cross sectional view of a power adaptation to my shaver.

Fig. 7 is a plan view partially in section of a power shaver showing how the blade may be 45 placed at right angles to the one shown in Fig. 6.

Fig. 8 is a side elevation of another form the hand shaver may take.

Fig. 9 is an enlarged end view of a blade showing another shape it may take.

50 Fig. 10 is an enlarged cross sectional view of the shear type of blade in a rectangular shape.

Like reference characters refer to like parts throughout the several views.

The shaver consists of a cylindrically shaped 55 blade 1, having the cutting edges 2. It may be

seen in Fig. 2, that these edges are normally held apart preferably by the spring of the blade itself. The blade is kept from expanding too much, by the bores 3 of the operating caps 4 which are disposed at each end of the blade. I provide a 5 guard spring 5 that fits closely to the inside of the blade when expanded so that when the cutting edges of the blade are held against one's face the hair may enter the gap between the cutting edges but the skin or flesh is arrested and held out by the guard spring 5. It may be seen that this will permit a very close shave as the guard is in back of the cutting edges. To operate, the shaver is held between the thumb and second finger which fit the concave portions 10 6 of the caps 4. The first finger lies in the re-leaved portion 36 of the blade 1 and keeps the shaver from turning. The cutting edges 2 of the blade are held against the face, this permits the hair to enter between the cutting edges of 15 the blade. Pressure may now be exerted on the caps 4 by the thumb and second finger, this causes the blade to contract as the tapered bores 7 act as cams on the ends of the blade 4. When the cutting edges come together they of course, 20 cut the interposing hair and as the pressure on the caps 4 is released the guard spring and the spring of the blade cause the caps to return to their starting positions. If this operation is repeated rapidly one may move the shaver on the 25 surface of the face thus removing the entire beard. The guide 8, keeps the blade from turning in the caps.

In Figs. 4 and 5 I show a shear type of blade that may be used if desired. It can be seen that the ends of the blade lap, the outer end forming the guard having the apertures 9 for the hairs to pass through. As the blade is contracted the inner end 10 passes over the apertures thus 35 shearing any hair that may be therein. The 40 amount of blade contraction may be limited by the size of the inner bore 11. The slot 12 straddles the guide 8 and keeps the blade from turning in the caps.

The power model imparts motion to the blade 45 through the tension rod 13 which passes freely through the inner cap 4 but is secured to the outer cap 4 by the nut 14. The tension rod receives its motion from plunger 15 of the solenoid coil 16, all of which are within a non-conductive case 50 17. Current is supplied through the wires 18, one going directly to one side of the solenoid coil, the other going to the other side of the coil through the spring breaker circuit 19. When the current is turned on the plunger 15, is drawn 55

into the coil 16, when it reaches a predetermined point, the fiber rod 20 strikes the spring breaker 19 opening the circuit at the points 21. The coil being without energy the spring 22 returns the plunger 15 to its outward position allowing the points 21 to contact each other again and thereby energizing the coil 16. Thus it may be seen that the plunger 15 will move in and out with great rapidity. The plunger 15 is counterbored to receive the tension rod 13, and is retained by the collar 23 which may be pressed or screwed to the plunger. The rod 13 passes freely through the collar 23 but its movement is limited by the collar 24 which is secured to the rod 13. It may be seen that the plunger 15 has free motion until it nears the inner end of its stroke, when the collar 23 strikes the collar 24 causing the outer cap 4 to move toward the inner cap 4 thereby contracting the blade 1. This construction permits the use of a much smaller coil and plunger as the kinetic energy of the plunger is utilized. If it becomes necessary to replace the blade, the nut 14 and the outer cap 4 may be removed and a new blade installed. The case is held together by the pins 25 which pass through the case 17 and into the combination end and inner cap 4, and the end 26 to which the points are secured. The coil 16 is held between the grip of the end pieces. I provide the cores 31 to the cap 4 so as to limit the contraction of the blade in order to obviate damage to the cutting edges.

In Fig. 7 is shown a shaver wherein the blade is at right angles to the solenoid. The solenoid and tension bore are the same as the one described above. The chief difference being that the caps 4 are secured to the arms 27, that are hinged at 28. The tension rod 13 is connected to the toggle links 29, which in turn are hinged to the arms 27 at 30. When the solenoid is energized the toggles pull the arms 27 inward thus contracting the blade 1, causing its cutting edges to operate. The arms 27 as shown are not quite parallel but when the solenoid is energized they are, thus insuring uniform pressure on the ends of the blade at the cutting point. The blade may be replaced in this model by removing the screws 28 from the case 32.

In Fig. 8 is a tong type of shaver having a handle 33, and a lever 34, the two being commonly hinged by the pin 35. The blade 1 is held by the jaws formed to hold it, and by holding the handle and pressing on the lever it will contract the blade.

While the form of mechanism herein shown and described is admirably adapted to fulfill the objects primarily stated, it is to be understood that it is not intended to confine the invention to the one form of embodiment herein shown and described as it is susceptible of embodiment in various forms all coming within the scope of the claims which follow.

I claim:

1. A one piece shaver blade rolled into a cylinder with its one free end overlapping the other free end, the outermost end having apertures therein through which hair may pass, the inner free end disposed at one side of the apertures and capable of sliding past them when the blade is contracted and thereby cutting the hair that may extend through the apertures.

2. A dry shaver consisting of a blade made of a one piece sheet rolled into an open cylindrical shape so that its cross section resembles a C, said blade capable of being contracted until the cylinder section becomes a closed circle thereby cut-

ting the hair that may be in the opening of the blade, a guard disposed within the blade bridging the opening therein, and a pair of caps having tapered bores for contracting the blade disposed on the ends of the blade.

3. A dry shaver comprised of a one piece blade having opposed cutting edges, said blade rolled into a substantially cylindrical form so the cutting edges are normally held spaced a short distance apart, a guard consisting of a common coil spring disposed within the blade, a cap having straight bore for receiving the cylindrical blade and a tapered bore for contracting the blade so that the cutting edges will meet, disposed on each end of the blade.

4. A shaver blade consisting of a piece of tubing having a longitudinal cut the full length of its wall, said edges produced by the cut constituting the cutting edges which are normally spaced apart, a guard for bridging the gap between the cutting edges disposed within the blade, said blade capable of being deflected thereby permitting the cutting edges to meet.

5. A shaver blade consisting of a flat piece of stock, having two opposed cutting edges, said stock rolled into a cylindrical shape until the cutting edges nearly meet, said blade capable of being contracted until the cutting edges meet, and a guard disposed within the blade for bridging the gap when the blade is expanded.

6. A one piece shaver blade consisting of a rectangular piece of stock having cutting edges on two of its opposed edges, said stock rolled into a substantially cylindrical shape so that its cross section normally resembles a C in shape, its cutting edges being in spaced relationship, said cylindrical blade capable of being contracted diametrically to permit the cutting edges to come together.

7. A one piece combination guard and shaver blade rolled into a cylinder with its one free end overlapping the other free end, the outermost end having apertures therein through which hair may pass, the inner free end constituting the cutting edge disposed at one side of the apertures, said inner free end capable of sliding past the apertures when the blade is contracted cutting the hair that may extend through the apertures, and at least one slot at one end of the blade to keep it from turning when placed in its operating mechanism.

8. A shaver having a cylindrically formed blade whose cross section normally resembles a C in shape, said blade adapted to be contracted until its cutting edges meet, a coil spring guard disposed within the blade, a cap having a straight bore for retaining the blade when expanded and a tapered bore for contracting the blade disposed on each end of the blade, a solenoid coil disposed near one of the contracting caps, a movable plunger disposed within the coil, a spring for holding the plunger in an outward position, a set of breaker points in the coil circuit, a rod secured to the plunger for interrupting the coil circuit, a tension rod connecting the outer cap and the plunger, said caps adapted to be contracted by said solenoid actuated rod.

9. A shaver consisting of a one piece cylindrically shaped blade adapted to be contracted to operate, a cap disposed on each end of the blade, each cap having a straight bore for holding the blade when expanded and a tapered bore that is a continuation of the straight bore for contracting the blade when said caps are moved toward each other, each cap secured to the end of an

arm that is hinged at its opposite end, a pair of toggle links secured to the arms, and power means for imparting reciprocating motion to the toggles.

5 10. A shaver consisting of a one piece cylindrically shaped blade adapted to contract and expand in performing its cutting operation, a tonglike device for contracting the blade consisting of a handle and a lever each having one 10 extreme end formed into a semicircular jaw to fit the blade, said handle and lever commonly hinged near their jaw ends, the blade having

virtual spring tension for expanding itself and returning the handle and lever to its normal position.

11. A shaver blade consisting of a single piece of metal having cutting edges on two opposed edges, said piece of metal formed so that the cutting edges will meet when the blade is contracted, said cutting edges being normally held in spaced relationship by the virtual temper of the metal, and a guard disposed within the blade. 5 10

EDWIN JACOBSEN.
